Attorney, Agent, or Firm—Quarles & Brady

[57] CLAIM

The ornamental design for a tub or the like, as shown and described.

DESCRIPTION

FIG. 1 is a perspective view taken from the top, front and left side of a tub or the like showing our new design;

FIG. 2 is a top plan view thereof;

FIG. 3 is a cross-sectional view taken on line 3—3 of FIG. 2; and

FIG. 4 is a cross-sectional view taken on line 4—4 of FIG. 2.

The fragmentary broken line representations of a deck in FIG. 1 and of holes in FIGS. 1, 2 and 4 are for the purpose of illustration only.

FIG. 4
